UNITED STATES PATENT OFFICE.

CARTER C. ARMSTRONG, OF CINCINNATI, OHIO.

VALVE FOR DOWN-SPOUTS AND THE LIKE.

1,134,717.

Specification of Letters Patent.

Patented Apr. 6, 1915.

Application filed January 30, 1913. Serial No. 745,064.

To all whom it may concern:

Be it known that I, CARTER C. ARMSTRONG, a citizen of the United States, and a resident of the city of Cincinnati, in the county of Hamilton and State of Ohio, have invented certain new and useful Improvements in Valves for Down-Spouts and the like, of which the following is a full, clear, and exact description, reference being had 10 to the accompanying drawing, forming part of this specification.

The object of my invention is to provide a suitable valve for down spouts which are connected with the sewer to prevent the 15 sewer gas from passing up through the down spout at the same time that free outlet for the gas is provided.

In municipalities where down spouts are required to be connected directly with the 20 sewer, it is also usually required that there shall be no trap to prevent the free escape of sewer gas through the sewer connection, and therefore no trap of the usual construction can be installed, and as a result the gas 25 has ordinarily free outlet through the down spout. This gas has a very injurious effect on the down spout pipe and in a very short time the gases passing up through the pipe cause 30 rust and decay and the down spout must be removed, which under other conditions would last for many years.

It is to obviate this difficulty and to prevent the sewer gases from escaping through 35 the down spout, and at the same time to provide for the free escape of the gases that my invention is directed, and it consists of that certain novel construction and arrangement of parts to be hereinafter particularly pointed out and claimed.

40 In the drawings, Figure 1 is a central vertical section of my improved construction. Fig. 2 is a transverse section, taken through the center of the barrel. Fig. 3 is a side elevation of my device very much reduced 45 in size.

An ordinary down spout pipe for rain water from the roof is indicated at 1, with sewer connecting pipe 2. At the connection of these two pipes my device is installed, usually at or near the ground. It 50 comprises the cylindrical barrel 3, with one end turned upwardly and provided with a cap 4, preferably screwthreaded thereon.

This cap is provided with a hole 5, for the 55 free escape of sewer gas at all times.

The barrel 3 is formed with a down spout connection 6 and a sewer connection 7. The barrel is inclined somewhat from the horizontal toward the down spout connection, and in the lower end is formed with a conical seat 8, upon which the ball valve 9 is normally seated, owing to the incline of the barrel, to close the passage into the down spout. A track 10 is provided in the barrel over the sewer outlet to prevent the ball valve, when moved from its seat, closing the sewer opening. There is thus always a free outlet for the sewer gas through the barrel and opening 5 in the cap. Gas, however, cannot find its way into the down spout as this passageway 70 is closed by the ball valve. The ball valve is of light material, as of hollow rubber or cork, and when rain water descends through the down spout, the ball is pushed away into the upper end of the barrel. If a large 75 volume of water is discharged by the down spout, the ball valve is carried up to close the opening 5, so that the rain water can never escape through the opening 5 in the barrel.

80 My invention is readily and easily applied to the end of the down spout at the sewer connection.

By removing the cap 4, access may be always had to the barrel to clean out the same 85 and remove any obstruction that may descend the down spout, and for insertion of the ball valve.

The fact that the opening 5 is always provided into the barrel, establishes a strong 90 air suction up through the down spout, so that under normal conditions the ball is held firmly on its seat, preventing any passage of sewer gas up through the pipe. Of course when the water descends through the 95 pipe, this suction is overcome and the ball dislodged from its seat, to return again both by gravity and the suction through the pipe.

Having thus described my invention, what 100 I claim as new and desire to secure by Letters Patent, is:—

1. In a device of the character specified, a barrel, a down spout, and a sewer pipe connected thereto so as to form a T-joint 105 of which the down spout and the barrel form the branches, the barrel turned up at its free end, with an opening in the free end thereof, a ball valve, a trackway over the sewer pipe connection with the barrel to 110

prevent the ball from seating therein and a valve seat about the down spout connection with the barrel, for said ball.

2. In a device of the character specified, a
5 barrel, a down spout, and a sewer pipe connected thereto so as to form a T-joint of which the down spout and the barrel form the branches, the barrel turned up at its free end, with an opening in the free end
10 thereof, a ball valve, a trackway over the sewer pipe connection with the barrel to prevent the ball from seating therein and a valve seat about the down spout connection with the barrel and about the opening in
15 the free end of the barrel, for said ball.
3. In a device of the character specified, a

barrel portion, a down spout and a sewer pipe, said barrel being provided with openings for the spout and pipe, and having an opening to the outer air, a valve seat about 20 the down spout opening, a ball valve to normally seat thereon, and means for preventing the ball valve from blocking the opening for the sewer pipe, whereby a free outlet is formed for sewer gas through the barrel without permitting the same to enter the 25 down spout.

CARTER C. ARMSTRONG.
